FOREIGN PATENT DOCUMENTS

DE 102 36 945 A1 3/2004

Primary Examiner — Ania Aman(74) *Attorney, Agent, or Firm* — Shook, Hardy & Bacon L.L.P.(57) **CLAIM**

The ornamental design for a fire pit as shown and described.

DESCRIPTION

FIG. 1 is a top, front, right perspective view of a fire pit of the present invention;
 FIG. 2 is a front elevation view thereof;

FIG. 3 is a left side elevation view thereof;

FIG. 4 is a right side elevation view thereof; and,

FIG. 5 is a top plan view thereof.

The evenly spaced broken lines shown in the drawings depict environmental subject matter only and form no part of the claimed design. The dash-dot broken lines depict the bounds of the claim and form no part of the claimed design. Rear and bottom plan views have been omitted as they form no part of the claimed design.

1 Claim, 4 Drawing Sheets(56)
